FIG. VI.

INVENTOR:
EMIL PANEK

Emil B. Mueller

UNITED STATES PATENT OFFICE.

EMIL PANEK, OF CLEVELAND, OHIO, ASSIGNOR TO THE GLOBE MACHINE & STAMPING CO., OF CLEVELAND, OHIO.

HINGE CONSTRUCTION.

1,374,602.

Specification of Letters Patent. Patented Apr. 12, 1921.

Application filed February 27, 1919. Serial No. 279,503.

To all whom it may concern:

Be it known that I, EMIL PANEK, a citizen of the United States, residing at No. 4616 Pershing Ave., city of Cleveland, in the 5 county of Cuyahoga and State of Ohio, have invented a new and useful Improvement in Hinge Constructions, of which the following is a specification, the principle of the invention being herein explained and the best 10 mode in which I have contemplated applying that principle, so as to distinguish it from other inventions.

My invention relates generally to a hinge construction and more particularly to a 15 flush bead hinge. The drawing exemplifies the application of my invention to an automobile box accessory which is surrounded by a bead at or near the point where the hinge action is to take place.

The object of my invention is to provide a 20 simple, durable and economical construction and to incidentally improve the appearance of the whole.

Adverting to the drawings:

Figure I is an elevation of the upper portion 25 of the rear of a box with a cover hinged thereto after the manner of my invention.

Fig. II is a section on line II—II of Fig. I.

Fig. III is a section on line III—III of 30 Fig. I.

Fig. IV is a perspective view of the rear side of a box with the hinge and cover removed.

Fig. V is a perspective view of the hinge.

Fig. VI is a perspective view of the hinge pin.

Inasmuch as the two hinge constructions shown are of duplicate formation throughout only one need be described and accordingly the singular number will be employed.

The rear side 1 of a box body is provided near its upper edge portion 2 with an outwardly curved bead 3. The bead portion 3

is slotted out at 4 as best appears in Fig. IV. A cover 5 having a lower rear edge portion 6 is adapted to inclose the edge portion 2 as is shown in Figs. II and III. A hinge leaf 7 is spot welded at the two points 8 to the portion 6 of the cover in such a way that the bottom of the hinge leaf depends below the 45 lowermost edge of the portion 6 of the cover. Such bottom of the hinge leaf is curved to one side at 9 to form a cylindrical tube 50 adapted for insertion through the slot 4 and to be of complementary contour. It is to 55 be understood that the side toward which the bottom 9 of the hinge leaf is rolled up is the inside of the hinge leaf so that the tubular portion 9 is mainly disposed inwardly of the outermost line of the bead 3, the outside of the hinge leaf being however substantially flush with the line of greatest projection of the bead 3 as may be seen on inspection of either Figs. II or III. Passed 60 through the tubular portion 9 and occupying 65 the concavity of the bead 3 on each side of the slot 4 is a hinge pin 10 which is, of course, put in place after the portion 9 has been inserted through the slot 4. It is preferable to spot weld the hinge pin at two 70 points 11 to the bead 3 in order to prevent its dislodgement.

I claim:

A hinge construction comprising a pair of members one fashioned with concavo-convex beads alined along and spaced from one 75 edge also separated from each other by a slot and the other with a hollow extremity conforming in shape to said beads, and adapted to be accommodated by said slot for securing said members in such position. 80

Signed by me, this 7th day of February, 1919.

EMIL PANEK.
